UNITED STATES PATENT OFFICE.

ALFRED W. FRENCH, OF PIQUA, OHIO.

OIL-CAKE-TRIMMING MACHINE.

No. 802,085.

Specification of Letters Patent.

Patented Oct. 17, 1905

Application filed December 16, 1904. Serial No. 237,107.

To all whom it may concern:

Be it known that I, ALFRED W. FRENCH, a citizen of the United States, residing at Piqua, in the county of Miami and State of Ohio, have invented a new and useful Improvement 5 in Oil-Cake-Trimming Machines, of which the following is a specification.

This invention relates more particularly to oil-cake-trimming machines of the kind in 10 which the cakes are moved one after another by conveyers over a horizontal table past the cutters or knives which trim off the soft edge portions of the cakes.

The object of the invention is to provide 15 efficient cutters of simple, inexpensive, and durable construction for cutting off the corners of the cakes.

In the accompanying drawings, consisting 20 of two sheets, Figure 1 is a front elevation of a cake-trimming machine embodying the invention. Fig. 2 is a plan view thereof. Fig. 3 is a plan view, on an enlarged scale, of the corner-cutters. Fig. 4 is a sectional elevation of the corner-cutters in line 4-4, Fig. 3. Fig. 25 5 is an end elevation, on an enlarged scale, of the corner-cutters.

Like numerals of reference refer to like parts in the several figures.

The machine illustrated is of that kind in 30 which the conveyers and cutters are so arranged that the cakes are first moved in one direction and have two opposite edges trimmed and are then moved in a direction at right angles to the first-mentioned direction and 35 have the remaining two edges trimmed. As the corner-cutters forming the subject-matter of this invention are ordinarily used for cutting off the corners of the cakes after their edges have been trimmed and as it is desirable 40 to remove both the soft edges and corners in a single operation in one machine, the corner-cutters are herein shown and described as a part of a machine of the kind mentioned which first trims the several edges of the cakes. 45 The corner-cutters can, however, be used independently of edge-trimming mechanism and in other kinds of trimming-machines.

The horizontal work-table is composed of two portions 1 and 2, which are arranged at 50 right angles to each other and over which each oil cake 3 is moved successively. The primary portion 1 of the table is provided with a conveyer 4, which may consist of two parallel chains, and the secondary portion 2 55 of the table is provided with a conveyer 5, which may consist of a single chain. Each

chain is arranged with its upper portion in a longitudinal slot or groove 6 in the table and is provided with projecting pushers 7 at suitable distances apart. These pushers engage 60 against the rear edges of the cakes and push the latter forwardly over the table. The conveyer-chains run around sprocket-wheels 8 and are driven by suitable mechanism (not shown) at a relative speed such that the primary conveyer will not feed the cakes to the secondary conveyer faster than the latter moves them past the secondary cutters. The primary and secondary portions of the table have raised side portions 9, which form guides 70 between which the cakes are confined laterally.

The cakes are piled on the primary table in a feed-receptacle which consists of upright bars 10 and 11, secured, respectively, to the 75 table and to a cross-piece or bridge 12. The uprights 11 are vertically adjustable on the bridge, so that their lower ends can be so adjusted with reference to the table that they will allow only the lowermost cake of the pile 80 to be pushed out by the pusher of the conveyer and will retain all the other cakes.

Each part of the work-table is provided with edge-trimming cutters of any known or suitable kind arranged on opposite sides of the 85 path of the cakes. Stationary cutters arranged in sets are shown, each set consisting of several knives located one behind the other and at different distances from the path of the cakes or in echelon, so that each cake in moving past the set of cutters comes in contact with one cutter after another. Each cutter removes a thin strip from the edge of the cake. The number of cutters in each set may be more or less, three being shown in the primary sets and two in the secondary sets. 90

The mechanism for cutting off the corners of the cakes is preferably constructed as follows: Two oppositely-disposed movable holders 13 are located at opposite sides of the path 100 of the oil cakes, preferably on the secondary portion of the table in rear of the secondary edge-cutters. Each holder is provided with an outwardly-facing oblique front knife 14 and an inwardly-facing oblique rear knife 15. 105 The two front knives converge rearwardly, or in the direction in which the cake is moved past the same, while the rear knives diverge rearwardly. In the construction shown the knife-holders are slidably mounted on a fixed transverse horizontal bar 16 and are pressed against adjustable stops 17 on said bar by 110.

springs 18, connecting-arms projecting from the knife-holders and stops. The stops 17 can be adjustably secured to the bar by screws 19 or other means. The rearwardly-converging 5 front knives are pressed apart as the cake enters between them, thereby producing two oblique cuts which remove the front corners of the cake, and the two knife-holders are held apart by the cake bearing against depending portions 20 on the holders. When 10 the cake passes these bearing portions of the holders, the latter approach each other under the pressure of the springs 18 and cause the diverging rear knives to produce two oblique 15 cuts which remove the rear corners of the cake. The rear corner-cutters are secured to and depend from shanks 21, adjustably secured to the holders, as by screws 22, so that they can be properly adjusted with respect to 20 the front cutters. While corner-cutters constructed as described are deemed preferable, the holders can be movably mounted and pressed toward each other in other ways and the construction otherwise changed without 25 departing from the invention.

The cakes can be centered on the table between the edge or corner cutters, if necessary, by spring-guides, such as indicated at 23, Fig. 2, or by other known devices, and they are 30 held down on the table while being moved along by rollers 24 or other weighted devices which bear upon the cakes.

The operation of the machine is as follows: The cakes are piled in the feed-receptacle upon 35 the primary portion 1 of the table. This receptacle holds all of the cakes of the pile against movement, except the lowermost cake. The cakes are moved from the bottom of this pile one after another by the pushers 7 on the 40 conveyer-chains 6 past the opposing cutters on the primary portion of the table and have their end edges trimmed in passing these cutters. At the end of this portion of the table each cake is transferred upon the secondary 45 portion 2 of the table and then moved over this part of the table in a direction at right angles to the first-described movement. On this secondary portion of the table the cakes are moved past the second set of edge-cutters 50 13 and have their sides trimmed. After the ends and sides have been so trimmed the cakes are moved past the corner-cutters and have their corners cut off.

I claim as my invention—

55 1. In a trimming-machine, the combination of cutters for removing portions of the side

edges of the cakes, cutters for removing the corners only of the trimmed cakes, and means for moving the cakes first past the edge-cutters and then past the corner-cutters, substantially as set forth. 60

2. In a trimming-machine, the combination of cutters arranged on opposite sides of the path of the cakes for removing portions of the side edges of the cakes, cutters arranged on 65 opposite sides of the path of the cakes in rear of the edge-cutters for removing the corners only of the cakes, and a conveyer for moving the cakes successively past the edge-cutters and corner-cutters, substantially as set forth. 70

3. The combination of cutters for removing the corners of the cakes by the movement of the one past the other, and means which prevent the cutters from action on the side edges of the cake, substantially as set forth. 75

4. The combination of means for moving the cakes, and cutters for removing the corners of the cakes, said cutters being held by the cakes from action on the side edges of the cakes, substantially as set forth. 80

5. In a trimming-machine, cutters which remove the corners only of the cakes and past which the cakes are moved and which act automatically to remove first the front corners and then the rear corners of the cakes, substantially as set forth. 85

6. In a trimming-machine, corner-cutters past which the cakes are moved, said cutters having knives for removing the front corners of the cakes and other knives for removing 90 the rear corners of the cakes, substantially as set forth.

7. In a trimming-machine, corner-cutters past which the cakes are moved comprising rearwardly-converging knives and rearwardly-diverging knives, substantially as set forth. 95

8. In a trimming-machine, the combination of movable holders, means for pressing the same yieldingly toward each other, rearwardly-converging cutters secured to said holders, bearing portions on said holders which engage the cakes, and rearwardly-diverging cutters on the holders in rear of said other cutters, substantially as set forth. 100

105 Witness my hand this 13th day of December, 1904.
